DRAIN STOPPER

Herbert Trotman, Bayside, N. Y.

Application December 11, 1939, Serial No. 308,637

1 Claim. (Cl. 4—293)

The invention relates to a drain stopper and more especially to a strainer cap or closure for sinks, laundry tubs or the like.

The primary object of the invention is the provision of an article of this character wherein the strainer disk covering a drain opening within a sink, laundry tub or the like can be sealed to prevent water or other liquid supplied thereto from discharge through the said drain opening and such article is of a construction to assure a watertight seal at the drain opening whether the strainer disk be countersunk in this opening or flush with the bottom of the sink, tub or the like.

Another object of the invention is the provision of an article of this character wherein there is provided a grip so that the said article can be conveniently placed and removed, the article being constructed for separable anchorage with the drain plate, disk or the like covering a drain opening in a sink, tub or other container for liquid and when applied will not become displaced for the opening of the drain and the discharge of liquid from the sink, tub or other container.

A further object of the invention is the provision of an article of this character wherein the construction thereof is novel and when applied to a perforated drain disk or plate assures a sealing of such drain to prevent water flow from the sink, tub or the like through the said drain, the anchoring medium for the article being built therewith in a novel manner.

A still further object of the invention is the provision of an article of this character, which is simple in its construction, thoroughly reliable and efficient in operation conveniently handled for ready and easy application and removal, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention and pointed out in the claim hereunto appended.

In the accompanying drawing:

Figure 1 is a fragmentary vertical sectional view through a drain for a sink, tub or the like showing the article constructed in accordance with the invention applied thereto.

Figure 2 is a view similar to Figure 1 showing

a slight variation in the form of a strainer disk or plate with the article applied thereto.

Figure 3 is a vertical sectional view through the article and taken at substantially right angles to the section shown in Figures 1 and 2.

Figure 4 is a top plan view of the article.

Figure 5 is a bottom plan view thereof.

Figure 6 is a perspective view of the anchoring medium removed from the article.

Similar reference characters indicate corresponding parts throughout the several views in the drawing.

Referring to the drawing in detail, A designates generally a portion of the bottom of a sink, tub or the like, B the drain opening therefor while C is a flat perforated strainer disk or plate covering the drain opening B. This disk or plate C, as is conventional, has seating in the sink, tub or the like A concentrically with respect to the drain opening B and in this instance, as is shown in Figure 1 of the drawing, the upper face of the said disk or plate C is substantially flush with the bottom face of the sink, tub or the like.

Adapted for application to the disk or plate C is a stopper or closure cap D which constitutes the present invention and comprises a circular-shaped, inherently yieldable body 10, preferably made from rubber, its central portion at the upper side thereof being concaved at 11 while the periphery of said body 10 is formed with an annular flange or rim 12 which is slightly outwardly flared and is disposed concentric to a normally flat bottom face 13 to the said body 10. The body 10 including the flange or rim 12 creates a cupped lower or bottom side to the article, the latter being of a diameter substantially equal to or slightly greater than the size of the disk or plate C.

Bridging the cavity 11 and following a transverse center axis of the body 10 is an upstanding upwardly arched gripping rib 14 creating a finger hold on the body 10 convenient for the hand placement and hand removal of the article in the use thereof.

Embedded in the rib 14 is an anchoring medium in the form of an inverted substantially U-shaped bail 15, preferably made from a single length of wire. Its tines or side prongs 16 are extended exteriorly of the body 10 beyond the flat bottom face 13 thereof and have bent therefrom reversely extending laterally directed terminal hooks 17. These hooks are adapted for insertion in selected perforations 18 provided in the disk or plate C for the latching or the an-

- choring of the article in place and in a sealing condition about the disk or plate C for the closure of the drain opening B. In this manner the strainer disk or plate C can be sealed against 5 discharge of liquid therethrough from the sink, tub or other liquid container through the drain therefor.

- In Figure 2 of the drawing the strainer disk 19 in contradistinction to being flat or straight has 10 its center area depressed or of concavo convex formation. To have the stopper or closure seal this type of strainer disk or plate 19, it is necessary to depress the body 10 of the said stopper or closure with the flange or rim 12 through 15 contact with the said disk or plate becoming outwardly spread and effecting a sealed joint between the latter and the said stopper or closure. This depressing of the body 10 enables the hook terminal 17 of the bail 15 to become 20 latched with the plate or disk 19 on the passage of the side members 16 of the said bail through selected perforations 20 in this plate or disk 19 and in this manner anchorage of the stopper or closure therewith is assured.
- 25 The bail 15 by being embedded in the rib 14 can be readily manipulated directly from the said rib for the latching of the stopper or closure and also the unlatching thereof and additionally this bail 15 reinforces the said rib.
- 30 The body 10 and the flange or rim 12 has the requisite yieldability or inherent elasticity for

the successful fitting of the article to a strainer disk or plate and the easy removal of such article therefrom. The article when applied assures a perfect seal of the drain opening B so that liquid within a sink, tub or the like can not flow through the strainer disk or plate into the drain opening B for the emptying of the liquid from the said sink, tub or the like.

5

What is claimed is:

An article of the kind described for use at a 10 drain opening having a perforated strainer disk covering the same, comprising an imperforate resilient body for sealing the strainer disk when superimposed thereon and having a peripheral annular flange for contact with said disk at its 15 margin, a rib formed with the body centrally of its uppermost side and disposed crosswise a distance thereof for effecting a finger grip, an anchoring medium of inverted substantially U-shaped bail formation made from a single 20 length of wire partially embedded centrally within the body to have the intermediate portion reinforcing the rib with the tines of the bail formation extended exteriorly of the body beyond its lower face, and reversely extending laterally directed terminal hooks formed from said tines for insertion in selected perforations in said disk whereby the flange will press against the said disk to have the body in a sealing condition about the said disk.
